JOURNAL BOX PACKING

Charles F. Jordan and Charles L. Faris, Lewiston, Idaho

Application April 25, 1958, Serial No. 730,877

3 Claims. (Cl. 308—88)

This invention relates to railroad rolling stock and pertains more particularly to a packing assembly for use in railway car truck journal boxes, for supplying lubricant to the journals of truck axles supported therein.

In accordance with present practice, the most prominent way of lubricating the journals of truck axles in railway cars is to simply stuff the journal boxes with cotton waste with the journal boxes to contain a supply of lubricant which is soaked up by the cotton waste and in wick-like fashion to be applied to the journal of the truck axle. Although this system is subject to certain disadvantages, it has proved to be the most practical manner of maintaining proper lubrication under most circumstances. Many other solutions have been proposed, but none to our knowledge, has proved both practical and successful. One of the main disadvantages of such a system is the tendency, upon loss of lubricant, for the journal and its associated bearing to become extremely hot causing the cotton waste to smolder and at times to catch on fire, such condition being known in the trade as a "hot box." This condition is caused by the premature loss of lubricant from the journal box and may be occasioned for several reasons. However, the most common reasons are the loss of lubricant through the dust guard opening of the journal box due to the railway car running or standing on a curve and the loss of lubricant through the dust guard opening of the journal box due to the entrance of water, snow, ice or the like into the journal box which raises the level of the lubricant and permits the same to flow outwardly of the journal box through the dust guard opening therein. The dust guard openings of journal boxes are conventionally provided with seal elements but it is well known that these assemblies quickly become worn to such an extent as to be ineffective for the purpose of preventing the entrance of water, snow or the like into the journal box such that a collection of such substance within the journal box will raise the level of the lubricant therewith permitting escape of the lubricant through the dust guard opening. It is of primary concern in connection with this invention to provide an improved and novel packing assembly for journal boxes of railway cars which will overcome the inherent disadvantages of conventional constructions.

Another object of this invention is to provide improvements in packing assemblies for the journal boxes of railway cars wherein provision is made for effectively sealing the lower portion of the dust guard opening therein against the entry of moisture and the like into the interior of the journal box.

A further object of this invention is to provide improvements in packing assemblies for journal boxes of railway cars including a tongue member having a transverse strip along the inner end thereof which is adapted to be placed at the inner side of a dust guard opening in a journal box to effectively seal against the entrance of moisture thereto through the dust guard opening and

2

wherein endless roller members are associated in folded relationship above the tongue for engagement with the undersurface of the journal of an associated truck axle and wherein such rolls cooperate with the tongue and strip associated therewith to effectively hold the same in place to seal against the moisture into the interior of the journal box.

- A further object of this invention is to provide improvements in devices of the character described incorporating a pair of endless roll elements made of compressible, flexible and absorbent material, there being a pair of such rolls, one disposed within the other and each being of a predetermined length and of a predetermined circumferential extent so as to properly lie, in folded relation, within a journal box and with the rolls being of sufficient thickness such that when soaked with lubricant, their combined thickness will effectively engage the uppermost fold of the assembly against the undersurface of a railway truck axle journal.
- Still another object of this invention is to provide improvements in packing assemblies for railway car journal boxes including a nested pair of endless rolls or belt formed of flexible, compressible and absorbent material for disposition beneath the journal of a truck axle within a journal box and overlying an elongate tongue member resting upon the bottom of the journal box and having a transverse strip across its inner end held in place by the rolls and located at the dust guard opening of the journal box and effecting a seal thereto.
- These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is an exploded perspective view of the improved packing assembly;

Figure 2 is a vertical section taken through a journal box and illustrating the disposition of the improved packing assembly therewith;

Figure 3 is a vertical section taken substantially along the plane of section line 3—3 in Figure 2 illustrating further details of the construction and disposition of the packing assembly within the journal box; and

Figure 4 is a horizontal section taken substantially along the plane of section line 4—4 in Figure 2 and illustrating still further details of the construction.

Referring at this time more particularly to Figure 1, the improved packing assembly will be seen to consist essentially of an outer endless roll or belt indicated generally by the reference character 10, an inner roll assembly indicated generally by the reference character 11 and a tongue assembly indicated generally by the reference character 12. The outer roll 10 is preferably formed of felt material characterized by its ability to be compressed and flexed and by its absorptivity. As is shown most clearly in Figures 2 and 3, the inner roll 11 is to be inserted or nested within the outer roll 10 and is coextensive in length therewith so that when the two rolls are folded or flattened as shown, they will provide a four ply assembly as occasioned by the upper and lower layers 13 and 14 of the outer roll and the upper and lower layers 15 and 16 of the inner roll. Preferably, the outer roll in actual practice is about 27 inches in circumference whereas the inner roll is approximately 20 inches in circumference, this allowing for the gaps 17 and 18 between the folded over ends 19 and 20 of the inner roll and the corresponding folded over ends 21 and 22 of the outer roll. This prevents bunching or interference between the two roll members and allows the

same to conform more properly to the contours of the confining space within the journal box assembly indicated generally by the reference character 23 within which they are placed.

The journal box 23 is of an entirely conventional nature and encompasses a main body portion 24 carrying a saddle bearing 25 and provided at its outer end with an access opening 26 provided with a conventional closure 27 and on its inner side with a dust guard opening indicated by the reference character 28. Associated with the dust guard opening 28 is the usual seal 29 which is intended to prevent the entry of foreign material such as water, dirt and the like into the interior of the journal box. However, as is well known, the seals 29 quickly become worn in service and their usefulness is largely destroyed in a relatively short period of time, particularly in the lower half thereof due to the nature of the bearing support between the journal box and the truck axle indicated by the reference character 30.

The truck axle 30 includes the usual end flange 31 and the journal portion 32 having, on the inner side thereof, an enlarged shoulder 33 with which the dust guard or seal 29 cooperates.

The tongue assembly 12 consists of an elongate main body portion 34 made of material similar to the outer roll 10 and which main body portion is of such length as to extend substantially from the area of the dust guard opening 28 of the journal box to adjacent the access opening 26 therein and is provided, at its outer end 35 with a flexible hand grip strap 36 for ease of manipulation thereof. A sealing strip indicated generally by the reference character 37 is integrally formed with or otherwise rigidly affixed to the inner end of the main body portion 34 of the tongue and extends transversely thereacross. This strip 37 is preferably of semi-circular configuration and the main body portion 34 of the tongue joins the same along a medial line extending along the inner face 38 of this strip, leaving portions 39 and 40 above and below the main body portion 34 as can be seen most clearly in Figures 1 and 2.

The height of the strip 37 is such as to bring the upper face 41 thereof at approximately the dust guard opening 28 or slightly thereabove, the purpose of which will be presently apparent.

For convenience of manipulating the assembly, the inner roll 11 is provided with a pair of hand grip straps 42 and 43 and it is to be understood that the material from which the inner roll 11 is made is similar to that of the outer roll 10 and the tongue assembly 12.

In using the device, the tongue assembly 12 is first inserted into the journal box in the position shown in Figures 2 and 3 with the strip 37 disposed at the extreme inner side of the journal box and adjacent the dust guard opening 28 therein. Thereafter, the nested inner and outer rolls 10 and 11 are inserted into position as shown and it will be noted that the total thickness of the assembly is such as to completely fill the vertical space between the bottom of the journal box and the undersurface of the journal 32 of the axle assembly and, consequently, the tongue body 34 is somewhat jammed as indicated by the reference character 50 so as to serve to lockingly hold the strip 37 in position against the inner face 51 of the rear wall 52 of the journal box and in proper position relative to the dust guard opening 28 therein. It is to be appreciated that after the packing assembly has been saturated with lubricant such as oil, the various plies thereof will swell somewhat to firmly and positively engage the undersurface of the journal 32. Also, as will be clearly seen in Figure 3, the circumferential lengths of the inner and outer rolls are such as to substantially completely fill the cross-sectional area of the journal box and to thereby prevent rolling or turning or twisting of the assembly while in place and in service.

It is to be noted that the two cylinders or rolls 10

and 11 are entirely independent and separate from each other so that each may be removed or replaced as desired or may be turned, as for example with the outer roll or cylinder 10, to present new rubbing surfaces against which the journal 32 is to bear and it is also to be noted that this member can easily be turned inside-out to present a completely new outer surface for engaging, at various times, the journal 32.

The purpose of the strip 37, and more particularly the disposition of the upper face 41 thereof is to form a continuation of the opening defining the dust guard opening 28 so that upon axial movement of the axle assembly 30, the shoulder 33 may bear upon and engage such surface 41 to effectively seal the assembly against the entry of foreign matter and more particularly of water which would tend to raise the level of lubricant within the journal box and cause loss thereof outwardly through the dust guard opening 28.

Actual experimentation with this type of lubricator indicates that the entire assembly will weigh in the neighborhood of 2 pounds when dry and will weigh approximately 10 pounds when saturated with oil, thus indicating that approximately one gallon of oil is absorbed by the assembly. This permits the packing assembly to be used, in a service, and operated such as to give the outer cylinder or roll a quarter turn every eighteen months or so while still effectively obtaining a lubricating action onto the journal 32.

The partial sealing strip 37 in association with the main body portion 34 of the tongue will effectively soak up, if necessary, any water entering the journal box assembly and the strip 37 will also effectively soak up any oil which might otherwise tend to run out the dust guard opening 28 when the railway car is standing or running on a curve. The tongue collects sediment and holds water, if any, and acts as a filter for oil as it is lifted to the journal. The partial sealing strip 37 also acts as a tell tale when the journal becomes overheated due to lack of oil, or other causes, as the felt pad touching the journal near the hub will put out a smoke warning that the journal is being overheated.

It is preferred that the rear edge of the strip 37, that is the upper rear edge thereof be slightly rounded so that lateral action of the axle 32 will not contact any square shoulder of this strip. Also, it is to be noted, that the opposite upper ends of this strip 37 are of smaller dimensions than the lowermost body portion of the strip. As a matter of fact, it is preferred that the strip 37 be tapered from its opposite ends for a distance of approximately four inches from those ends toward the lowermost and main central body portion of the strip.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A lubricating journal box assembly comprising a journal box having a partial bearing in the upper portion thereof, said journal box having opposed side walls on opposite sides of said bearings and extending therebelow and being joined by a bottom wall member, said journal box also having an inner end wall provided with a dust guard opening receiving the journal of a truck axle upon which said bearing is seated, a tongue assembly lying upon said bottom wall including a main body of flexible, absorbent material having a thick strip of material extending transversely across the inner end thereof, said strip being engaged against said inner end wall to form a partial seal in engagement with said journal, a pair of endless rolls, one disposed within the other, and each formed of absorbent, flexible material, said rolls being

disposed in flattened condition between said main body portion of the tongue and the undersurface of said journal to anchor said strip in place and being of a thickness to substantially completely fill the space between the tongue and the journal, and said rolls being of such circumferential length as to extend upwardly on opposite sides of said journal.

2. The combination of claim 1 wherein said tongue member is of greater length than said roll members so as to project outwardly therebeyond.

3. The combination of claim 1 wherein the inner

roll is of less circumferential extent as compared with the outer roll such as to leave spaces between the opposite folded ends of the inner roll and corresponding ends of the outer roll.
